(57) **CLAIM**

The ornamental design for a hand shower for traveling purposes, as shown and described.

DESCRIPTION

The patent or application file contains a least one drawing executed in color. Copies of this patent or patent application

publication with color drawing(s) will be provided by the Office upon request and payment of the necessary fee.

FIG. 1 is a top plan view of a first embodiment of a hand shower for traveling purposes in accordance our my design;

FIG. 2 is a top, front perspective view thereof;

FIG. 3 is a bottom plan view thereof;

FIG. 4 is a bottom, rear perspective view thereof;

FIG. 5 is a left side elevational view thereof;

FIG. 6 is a front elevational view thereof;

FIG. 7 is a right side elevational view thereof; and

FIG. 8 is a rear elevational view thereof;

FIG. 9 is a top plan view of a second embodiment of a hand shower for traveling purposes in accordance with my design;

FIG. 10 is a top, front perspective view thereof;

FIG. 11 is a bottom plan view thereof;

FIG. 12 is a bottom, rear perspective view thereof;

FIG. 13 is a left side elevational view thereof;

FIG. 14 is a front elevational view thereof;

FIG. 15 is a right side elevational view thereof; and

FIG. 16 is a rear elevational view thereof;

FIG. 17 is a top plan view of a third embodiment of a hand shower for traveling purposes in accordance with my design;

FIG. 18 is a top, front perspective view thereof;

FIG. 19 is a bottom plan view thereof;

FIG. 20 is a bottom, rear perspective view thereof;

FIG. 21 is a left side elevational view thereof;

FIG. 22 is a front elevational view thereof;

FIG. 23 is a right side elevational view thereof; and

FIG. 24 is a rear elevational view thereof;

FIG. 25 is a top plan view of a fourth embodiment of a hand shower for traveling purposes in accordance with my design;

FIG. 26 is a top, front perspective view thereof;

FIG. 27 is a bottom plan view thereof;

FIG. 28 is a bottom, rear perspective view thereof;

FIG. 29 is a left side elevational view thereof;

FIG. 30 is a front elevational view thereof;

FIG. 31 is a right side elevational view thereof; and,

FIG. 32 is a rear elevational view thereof.

The broken lines represent portions of the hand shower for traveling purposes in which the design is embodied that form no part of the claimed design. The portions of the hand shower for traveling purposes in which the design is embod-
